DESIGN FOR A BOLSTER FOR FLATWARE OR THE LIKE

Lewis Berk, Brooklyn, N. Y., assignor to American Merchandise Company, New York, N. Y., a co-partnership consisting of Harry Greenberg and Leo Josefsberg

Application June 29, 1933. Serial No. 48,595

Term of patent 3½ years

To all whom it may concern:

Be it known that I, LEWIS BERK, a citizen of the United States, residing at the borough of Brooklyn, in the county of Kings, city and State of New York, have invented a new, original, and ornamental Design for a Bolster for Flatware or the like, of which the following is a specification, reference being had to the accompanying drawing forming part thereof.

Fig. 1 is a top view of a bolster showing my new design.

Fig. 2 is a front view of the same.

Fig. 3 is a side view of the same.

Fig. 4 is a bottom view of the same.

The bolster is intended to be secured between the operating portion and the handle portion of a knife, fork or the like in the manner customary in the art, the bolster being a complete article of manufacture sold as such in the trade.

I claim:

The ornamental design for a bolster for flatware or the like, as shown and described.

LEWIS BERK.
